(57) **CLAIM**

The ornamental design for a vehicle front fender, as shown and described.

DESCRIPTION

FIG. 1 is a left side elevational view of a left vehicle front fender (the right vehicle front fender being a mirror of the left and is not illustrated);

FIG. 2 is a front elevational view of the vehicle front fender;

FIG. 3 is a rear elevational view of the vehicle front fender;

FIG. 4 is a right side elevational view of the vehicle front fender;

FIG. 5 is a top plan view of the vehicle front fender; and,

FIG. 6 is a bottom plan view of the vehicle front fender.

Shading is used to illustrate the curvature of the part and not color. Areas shown in or bounded by broken lines are not claimed. Views are orthogonal projections unless otherwise noted. The various views are not necessarily to scale in order to better illustrate the design.
